FLASH TUBE IGNITING DEVICE FOR
GASEOUS FUEL BURNERSCharles K. Strobel, Pittsburgh, Pa., assignor to
Robertshaw-Fulton Controls Company, a cor-
poration of Delaware

Application November 29, 1944; Serial No. 565,609

3 Claims. (Cl. 158—115)

1

This invention relates to lighting devices for gaseous fuel burners and, more particularly, to flash tube ignition for domestic oven burners.

Devices of this nature depend upon an open-ended tube of considerable length extending between the top burner pilot flame and the oven main burner to the end that a fuel-air mixture entering the tube at the oven burner end will cause the tube to become completely filled with the combustible fluid. Thus, upon reaching the pilot burner the mixture propagates a flame which flashes back through the tube and ignites the oven burner. In the present invention the fuel supply for the entering fuel-air mixture is conveyed through a lighter port adjacent the oven burner and entrains its air supply after leaving the port and before entering the flash tube. Consequently, the lighter port flame which is produced after the flash-back occurs is of the yellow type for reasons apparent hereinafter.

One object of the invention is to assist flame travel and air entrainment in a flash tube to ensure consistent ignition of the main burner.

Another object of the invention is to reduce the heat loss from the oven chamber due to the stack action of the flash tube.

Another object of the invention is to ensure rapid and consistent ignition of the oven burner under either hot or cold oven condition.

Another object of the invention is to secure desired flame travel in the tube over a wide range of flows, pressures and gas-air mixtures.

Another object of the invention is to eliminate critical features in the size, shape and relationship of parts to render the device universally applicable to existing gas ranges.

Another object of the invention is to avoid interference with satisfactory ignition due to clogging of essential orifices under service conditions.

Another object of the invention is to construct the device with relatively few parts which are simple to produce and assemble and occupy a minimum of space when installed in the range.

Other objects and advantages will become apparent from the following description taken in connection with the accompanying drawings, wherein:

Fig. 1 is a partial schematic view of a gas range showing the lighting device positioned in the oven chamber;

Fig. 2 is a partial cross section through the end of the lighting device adjacent the oven burner;

Fig. 3 is an end elevation of the portion of the device shown in Fig. 2; and

2

Fig. 4 is a cross section taken on the line IV—IV of Fig. 2.

Referring now more particularly to Fig. 1, the essential parts of the gas range comprise an oven main burner 10 positioned on one side of an oven wall 12 and having the usual ports 11 through which gaseous fuel is emitted to produce a main burner flame when ignited. A top burner pilot 14 is positioned on the other side of the oven wall 12 and at a considerably higher elevation than the oven burner 10. The top burner pilot 14 is supplied with fuel from any suitable source of gaseous fuel supply and produces a flame which may be of the constant burning type.

The lighting device comprises generally a flash tube 16 having a laterally extending portion 18 at one end positioned adjacent the flame of the top burner pilot 14. As appears in the drawing, the lateral portion 18 may depend slightly from a perpendicular relationship with the vertical portion of the tube 16 and is gradually curved at its junction therewith. The opposite end of the tube 16 extends laterally in the opposite direction from the portion 18 in the form of a curved portion 20 and terminates at a point spaced from the main burner 10. The tube 16 is clamped to the oven wall 12, as by the brackets 22, on the side opposite the oven burner 10 and the curved portion 20 extends through an aperture 24 formed in the oven wall 12 for this purpose.

The terminal end of the curved portion 20 is secured by an adapter 26 in sealing engagement with one member 28 of a generally cylindrical, tubular head element, designated by the reference numeral 30. Telescopically mounted on the member 28 is the other member 32 of the tubular head 30. A set screw 34 projects through the member 32 into engagement with the member 28 and serves to secure these members in adjusted relation with a portion of member 28 projecting into the end of member 32. The opposite end of the member 32 is closed by an end portion 36 and has an inlet connection 38 for gaseous fuel projecting laterally therefrom and communicating with a suitable source of gaseous fuel supply.

Preferably, the tubular head 30 extends at an angle of approximately 45 degrees from the vertical portion of tube 16 into the oven chamber with the closed end 36 positioned adjacent the main burner 10. It will be apparent that the set screw 34 may be loosened to permit adjustment of the telescoped members 28 and 32 to provide a desired positioning of the tubular head 30 with respect to the oven burner 10. However, it will

be understood that where such adjustment is not required the tubular head 30 can be formed from a single piece of material without departure from the essential characteristics of this invention.

The member 32 is provided with a plurality of elongated openings 40 in the side wall thereof adjacent the closed end 36. In order to facilitate forming these openings 40, the member 32 has its outer wall formed with a triangular shaped contour, as shown in Fig. 3, and the openings 40 are formed in the triangular sides leaving three ribs 42 therebetween which connect the closed end 36 with the generally cylindrical portion of the member 32. At least one of the openings 40 extends into proximate relation with the burner 10 for a purpose apparent hereinafter.

A lighter burner 44 is secured in the closed end 36 by means of a threaded projection 46 thereon and projects axially of the head 30 substantially equidistant of the ribs 42. A port 48 extends axially through the lighter burner 44 and communicates with a passage 50 in the closed end 36 which conveys fuel from the connection 38. Preferably, a second port 52 extends substantially perpendicular to the port 48 and in communication therewith and is located on that side of the lighter burner 44 nearest to the main burner 10.

The end of the member 28 which projects into the member 32 is provided with a countersunk or annular cone-shaped portion 54 which is preferably in axial alignment with the port 48 in the lighter burner 44. The cone-shaped portion 54 has its larger end facing the lighter burner 44 and this end is substantially the same size as the bore of the member 32 leaving no appreciable annular projection at the junction therewith. The smaller end 56 of the cone-shaped portion 54 may be truncated by a junction with a larger bore 58 in the member 28. The smaller end 56 of the cone-shaped portion is of substantially the same size as the bore of the flash tube 16. Thus, the bore 58 between the cone-shaped portion 54 and the tube end 20 forms an expansion chamber within the tubular head 30.

The expansion chamber 58 may be provided with communication with the atmosphere for use when desired. In this instance, an aperture 60 is formed through the wall of the member 28 adjacent the smaller end 56 of the cone-shaped member 54 and a set screw 62 may threadedly engage the walls of the aperture 60 forming a removable closure therefor. It will be understood that a plurality of such apertures could be provided. A collar 64 is slidably mounted on the member 32 and is adjustable by means of a clamping screw 66 therein so that the collar 64 may be moved partially across the adjacent triangular shaped portion to change the effective area of the openings 40.

When the flash tube 16 of this invention is installed in the range as shown schematically in Fig. 1, the open end of the portion 18 is positioned adjacent the flame of the top burner pilot 14. The tubular head 30 is positioned so that one of the lateral openings 40 is in proximate relation with the main burner 10 which has at least one port 11 directed toward the lighter burner 44. When fuel under pressure is supplied through the connection 38 to the lighter burner 44 the flow through the port 48 will entrain air through the lateral openings 40 and the flash tube 16 will become filled with a combustible fuel-air mixture. This mixture is ignited by the flame of the top burner pilot 14 and a flash-back

occurs through the tube 16 and head 30 which immediately causes ignition of the lighter burner 44. If the oven burner then is receiving gaseous fuel from the same or another source of supply as the connection 38 then a portion of the fuel from the ports 11 will flow into lighting proximity with the burner 44. The main burner, in turn, will be ignited by the flame at the lighter burner. The auxiliary port 52 of the lighter burner which projects towards the oven burner 10 facilitates the ignition thereof after the flash-back occurs.

By using a flash tube constructed as described, it has been found that the tube may be of smaller bore than those previously in use without interfering with satisfactory operation. For example, the bore of the flash tube of this invention may be three-eighths inch in diameter even where tubes of two feet or more in length are used. This small size bore reduces the heat loss from the oven burner chamber by stack action, as will be apparent.

It is believed that the advantages of this invention are principally due to the provision of the expansion chamber above the cone-shaped portion, as a wide operating range in conjunction with a minimum lighter port fuel flow is obtained. Various adjustments can be made to the length of the expansion chamber, the spacing of the lighter port from the cone-shaped portion and the air supply through the lateral openings to improve operation under certain lighter conditions. The latter two adjustments can easily be made by use of the adjustable features hereinbefore described in connection with the tubular head. It is apparent that different lengths of flash tube will be required under different range designs and that installation conditions may also differ.

As is generally known, a flash tube lighter port fuel-jet, burning with a yellow flame, must entrain all of the air supply required for proper flash tube action. Any interference with free air entrainment will affect operation of the flash tube. While it is impossible to state with certainty that the expansion chamber above the cone-shaped portion is responsible for the prevailing favorable condition in the flash tube of this invention, it appears that it either prevents a fuel-air mixture from being forced backward through the cone-shaped portion to hinder the air entrainment or it provides a pressure release ahead of the flame which likewise prevents a decrease in air entrainment. In addition, it appears that the truncated cone-shaped portion serves to enhance air entrainment and at the same time reduce explosive action back to the lighter port.

The foregoing advantages are obtained without reliance upon small relief openings or supplemental apertures or slots to assist air entrainment. Consequently, there is no interference with the operation of the flash tube by clogging of such openings as has heretofore been the case and a simple imperforate tube may be used. However, should it be found upon installation of the flash tube in the oven that unusual conditions render communication with the atmosphere desirable, then the small relief opening provided in the expansion chamber may be resorted to by removal of the set screw which normally closes this opening. Preferably the lighter port flame is centered relative to the cone-shaped portion and the flame thereof is sufficiently long to project just within the cylindrical end of the tubular head beyond the lateral openings. Such adjust-

ment gives satisfactory performance over a wide pressure range under both cold and hot oven conditions.

It will be apparent that various changes can be made in the arrangement and combination of parts and in the details of construction herein disclosed within the scope of the appended claims without departing from the spirit of the invention.

I claim:

1. A lighting device for a main gaseous fuel burner provided with at least one port and having a pilot burner remote therefrom and normally producing a flame, said device comprising a flash tube having one open end positioned adjacent the pilot burner and the opposite open end spaced from the main burner, a tubular head secured to said opposite tube end and terminating in a closed end adjacent the main burner, said head having a plurality of relatively spaced narrow ribs defining elongated openings in the side wall of said head adjacent said closed end, said openings being symmetrically arranged around said head and at least one of said openings being positioned to admit fuel from the one said port of the main burner into said head, an inlet connection in said closed end for fuel under pressure, a lighter burner projecting from said closed end axially of said head and terminating adjacent said openings to intercept fuel from said one port of the main burner, said lighter burner having an axial port communicating with said connection through which said fuel is adapted to flow and entrain sufficient air through said openings for filling said head and tube with a combustible fuel-air mixture to be ignited from the pilot burner and produce a flame at said lighter burner for igniting the main burner, said head having an interiorly cone-shaped portion projecting from the inner wall thereof between said opposite tube end and said openings in axial alignment with said lighter burner port and being positioned with the restrictive end thereof facing said opposite tube end, the wall of said head between said portions and said opposite tube end defining an expansion chamber.

2. A lighting device for a main gaseous fuel burner provided with at least one port and having a pilot burner remote therefrom and normally producing a flame, said device comprising a flash tube having one open end positioned adjacent the pilot burner and the opposite open end positioned spaced from the main burner, a tubular head including a pair of telescopic members adapted to be secured in adjusted relation, one of said members being secured to said opposite tube end and the other said member terminating in a closed end adjacent the main burner, said other member having a plurality of relatively spaced narrow ribs defining elongated openings in the side wall of said other member adjacent said closed end, said openings being symmetrically arranged around said other member and at least one of said openings being positioned to admit fuel from the one said port of the main burner into said other member, an inlet connection in said closed end for fuel under pressure, a lighter burner projecting from said closed end axially of said head and terminating adjacent said openings to intercept fuel from said one port of the main burner, said lighter burner having an axial port communicating with said connection through which said fuel is

adapted to flow and entrain sufficient air through said openings for filling said head and tube with a combustible fuel-air mixture to be ignited from the pilot burner and produce a flame at said

5 lighter burner for igniting the main burner, said head having an interiorly cone-shaped portion projecting from the inner wall thereof between said opposite tube end and said openings in axial alignment with said lighter burner port and being positioned with the restrictive end thereof facing said opposite tube end, the wall of said head between said portion and said opposite tube end defining an expansion chamber.

3. A lighting device for a main gaseous fuel

15 burner provided with at least one port and having a pilot burner remote therefrom and normally producing a flame, said device comprising a flash tube having one open end positioned adjacent the pilot burner and the opposite open

20 end spaced from the main burner, a tubular head including a pair of telescopic members adapted to be secured in adjusted relation, one of said members being secured to said opposite tube end and the other said member terminating in

25 a closed end adjacent said main burner, said other member having a plurality of relatively spaced narrow ribs defining elongated openings in the side wall of said other member adjacent said closed end, said openings being symmetrically arranged around said other member and at least one of said openings being positioned to admit fuel from the one said port of the main

30 burner into said other member, an inlet connection in said closed end for fuel under pressure, a lighter burner carried by said closed end and projecting axially into said head and terminating adjacent said openings to intercept fuel from said one port of the main burner, said lighter burner having an axial port communicating with said connection through which said

35 fuel is adapted to flow and entrain sufficient air through said openings for filling said head and tube with a combustible fuel-air mixture to be ignited from the pilot burner and produce a flame at said lighter burner for igniting the main burner, said one member having an interiorly cone-shaped portion projecting from the inner wall thereof at the other end from said

50 opposite tube end and in axial alignment with said lighter burner port and being positioned with the restrictive end thereof facing said opposite tube end, the wall of said head between said portion and said opposite tube end defining an expansion chamber, said expansion chamber being provided with an aperture in the side wall thereof adjacent the restrictive end of said cone-shaped portion, and a collar slidably mounted on said other member and adjustable over said openings to maintain said symmetrical arrangement and control the effective area thereof.
